CHARLES H. SPRAGUE, OF DES MOINES, IOWA

SYRINGE

Application filed October 6, 1931. Serial No. 567,323.

This invention relates to improvements in syringes and has particular reference to a fountain syringe employed in the treatment of internal organs such as the vagina.

5 An object of the invention is to provide an improved syringe of simple and practical construction which will be effective in the treatment of the vagina and other internal organs.

10 Another object is to provide an apparatus for simultaneously distending and applying heat and medicament to the vagina.

15 The above and other objects will appear more clearly from the following detail description, when taken in connection with the accompanying drawing, which illustrates preferred embodiments of the inventive idea.

In the drawing—

Figure 1 is a side elevation of one form of the device;

20 Figure 2 is a fragmentary longitudinal sectional view;

Figure 3 is an end elevation;

Figure 4 is a section on the line 4—4 of Figure 2; and

25 Figure 5 is a view similar to Figure 2 showing a slightly different form of the invention.

Referring particularly to Figures 1 to 4 of the accompanying drawing, the syringe is shown as comprising a hollow body portion or head, generally indicated by the numeral 6, made of a hard rubber composition or other suitable material and including the inner and outer walls 7 and 8 combining to form a medicament-receiving compartment 9. The inner wall 7 is of cylindrical formation and defines a centrally disposed opening in the head. The outer wall 8 is of tapered formation and at its outer enlarged end is internally screw-threaded to receive a removable end closure

30 10 also having a central opening 11 aligned with the opening formed by the inner wall 7. The end closure 10 has mounted therein a connection 12 utilized for the purpose of introducing a medicament into the compartment 9 from a suitable receptacle.

At the inner reduced end of the head 6 the same is provided with a plurality of spaced openings arranged in a circle and in which connections 13 are mounted for receiving thereover the open ends of the flexible tubes

14, commonly known as Dakin tubes. These tubes are provided with perforations 15 throughout their lengths, the perforations being more numerous adjacent the free or closed ends of the tubes than at the open ends thereof, whereby the medicament from the compartment 9 will flow through the perforations in greater quantities at the free ends of the tubes, so that when the device is in proper position the most beneficial results will be derived.

14, commonly known as Dakin tubes. These tubes are provided with perforations 15 throughout their lengths, the perforations being more numerous adjacent the free or closed ends of the tubes than at the open ends thereof, whereby the medicament from the compartment 9 will flow through the perforations in greater quantities at the free ends of the tubes, so that when the device is in proper position the most beneficial results will be derived.

In order to secure distension and apply heat to the vagina while using the device, the syringe further includes a flexible and elongated receptacle 16 made of any suitable material and open at one end. This receptacle has the portion thereof adjacent its open end mounted in the opening formed by the inner wall 7 while the remainder thereof extends longitudinally of and between the tubes 14 as clearly shown in Figure 1. To detachably secure the receptacle in position there is provided a plug 17 of a diameter slightly less than that of said opening and which may be slightly tapered so that upon insertion of the plug into the opening and the open end of said receptacle, the latter will be wedged in position with the open extremity overlapping the end closure 10. The plug is provided longitudinally thereof with passages 18 and 19 in the outer ends of which are disposed the inlet and outlet connections 20 and 21 respectively. The connection 20 is designed to be connected to a hot water bag or other suitable receptacle so that the receptacle 16 may be filled with heated water or other fluid to distend the same and at the same time apply heat to the parts to be treated. The inlet passage 19 is made slightly larger in diameter than the outlet passage 18 so that a back pressure will be created by the water circulating through the device which will maintain the receptacle 16 in a distended condition. It will be obvious that, if so desired, the inlet passage 19 may be made longer than the passage 18 by inserting one end of a short connection (not shown) similar to the connection 20 in the inner end of said passage 19.

In the operation of the device, after the same has been properly positioned in the vagina, the heated water may be permitted to circulate through the receptacle 16 and out of the passage 21 into a basin or other receptacle to secure proper distension and application of heat. At the same time the medicament may be permitted to flow into the compartment 9 and from thence through the perforations in the tubes 14 to the parts being treated.

In Figure 5 there is shown a slightly different form of securing means for the receptacle 16 and plug 17 wherein the closure 10 is provided with an annular flange 22 having a bayonet slot 23 therein for receiving a pin 24 carried by a reduced portion of the plug 17. With this construction the plug is securely held in position and at the same time is effective in maintaining the receptacle 16 in proper position.

What is claimed is:

1. In a syringe, a body portion including inner and outer walls forming a medicament-containing compartment, a plurality of perforated tubes carried by said body portion and having communication with said compartment, and means carried by said body portion for applying heat to and securing distension of parts to be treated.

2. In a syringe, a body portion including inner and outer walls forming a medicament-containing compartment, a plurality of perforated tubes carried by said body portion and having communication with said compartment, and a flexible fluid-containing receptacle carried by said body portion and extending longitudinally of and in close proximity to said tubes.

3. In a syringe, a body portion provided with a compartment and having an opening therethrough, a removable end closure for said compartment surrounding said opening, a plurality of perforated tubes carried by said body portion and communicating with said compartment, a liquid-containing receptacle having one end disposed in the opening in said body portion and engageable with said end closure and the remainder thereof arranged contiguous to said tubes, and a plug insertable into said opening and end of said receptacle to wedge the latter between said plug and the wall of said opening and said closure.

4. In a syringe, a body portion provided with a compartment and having an opening therethrough, a removable end closure for said compartment surrounding said opening, a plurality of perforated tubes carried by said body portion communicating with said compartment, a liquid-containing receptacle having one end disposed in the opening in said body portion and engageable with said end closure and the remainder thereof con-

fined within an area defined by said tubes, and a tapered plug insertable into said opening and end of said receptacle to wedge the latter between said plug and the wall of said opening and said closure.
